UNITED STATES PATENT OFFICE.

CHARLES R. MOORE, OF WYOMING, NEW JERSEY, ASSIGNOR TO WESTERN ELECTRIC COMPANY, INCORPORATED, OF NEW YORK, N.Y., A CORPORATION OF NEW YORK.

TELEPHONE TRANSMITTER.

Application filed January 23, 1923. Serial No. 614,356.

This invention relates to telephone transmitters, and the object is the improvement of transmitters by increasing their sensitivity, practically eliminating breathing 5 and increasing their stability.

In accordance with the general features of the invention there is provided a transmitter in which the chamber for the granular material is carried by, or forms a part of, a 10 loosely supported system, and a barrier between the electrodes causes the concentration of current at the area of maximum agitation of the granules.

In accordance with another feature the 15 distortive effect due to breathing, that is, the continual expanding and contracting of the various parts on account of the continually varying temperatures caused by the current through the granular material, is substantially reduced by loosely supporting relative to each other, the parts comprising the 20 system.

In its preferred form the transmitter is provided with a laminated diaphragm, each 25 of the outer laminations supporting at its center an annular electrode, and the intermediate lamination forming an insulating barrier between the electrodes and controlling the current path through the granular carbon, a chamber for which is formed by the 30 laminations. The assembled diaphragm is loosely supported between banks of paper or foil washers which are disposed on each side of it at its periphery, the diaphragm supporting means also supporting the laminations in juxtaposed relation.

Referring to the drawing:

Fig. 1 is a cross-section of a transmitter embodying the invention.

Fig. 2 is a cross-section through the diaphragm adapted for use in inertia type transmitters.

A disc 3, preferably of metal, has a cup shaped depression 4, the inside bottom surface of which may be insulated by coating it with an insulating varnish or covering it with any suitable insulating material 5. Fitted into the cup and forming the electrical contact with its marginal wall is an 45 annular electrode 6, preferably of brass gold-plated. A disc 7 of substantially the same diameter as the disc 3 is perforated at its center and provided with an oppositely extending flange 8, within which is fitted 50 a second annular electrode 9. Between discs

3 and 7 is disposed a third disc 10, preferably of insulating material such as mica or phenol plastic compound. The disc 10 is provided with a central aperture having a diameter somewhat less than the inside diameter of the smaller electrode 6. Closing the opening in disc 7 is a plunger 11, the face of which is preferably coated with an insulating compound. Supported against the edge of the flange 8 and the electrode 9 60 by the plunger 11 is a plurality of loosely disposed washers 12. The space between the plunger 11 and the electrode 8, and the annular 27 on the plunger 11 is preferably more than the combined thickness of the washers 12. The plunger 11 may be supported by any well-known means on a bridge 13 which, in turn, is supported on an annular member 14 by means of screws 16. Between a flange 15 on the member 14 and an 65 internal nut 20, the diaphragm 3 is loosely supported by a plurality of washers 17 of thin foil or paper disposed on each side thereof. The inside surface of the member 14 is preferably lined with insulation which 70 may be divided into two parts 18 and 19 as shown. The space between the nut 20 and insulation 18 should be somewhat greater than the combined thicknesses of the diaphragm 3 and the washers 17 so as to provide 75 air films between adjacent washers.

Supported against the annular member 14 by means of screws 21 is the usual perforated face plate 22 carrying a mouth-piece 23. The case 24 supports the member 14 in any 80 suitable manner.

In the modification shown in Fig. 2, the disc 7 of Fig. 1 is replaced by a disc 26 having a cup 27 similar to that of disc 3. With this form, which is suitable for inertia 85 type transmitters, the bridge 13 and the plunger 11 of Fig. 1 are not required.

With the type of transmitter button herein disclosed, the agitation between the carbon granules and the electrodes is reduced to a 90 minimum and confined to the region of maximum current density. By suitably proportioning the electrodes and the opening in the barrier 10, transmitters of practically any resistance may be obtained. Very stable 95 transmitters having a resistance of the order of 600 ohms may be readily provided by this structure, and are suitable for use on 48 volt telephone systems without the use of the usual transformer or induction coil.

The invention claimed is:

1. In a transmitter, a diaphragm comprising a pair of discs of substantially equal diameter each having a central laterally extended portion, an annular electrode fitted in each portion, and an insulating plate disposed between said electrodes and movable as a unit with said discs, said plate having a central aperture of less diameter than the inside diameter of either electrode.
2. In a transmitter, a diaphragm comprising a pair of discs of substantially equal diameter, one of said discs having a central laterally extending rim, an electrode fitted in said rim, the other of said discs having a central depression therein, an electrode in said depression, an insulating plate having a central aperture of less diameter than the inside diameter of either electrode disposed between said discs and said electrodes and a plurality of thin washers loosely disposed at the periphery of said diaphragm and on each side thereof for controlling the vibrations and supporting said discs and plate in juxtaposed relation.
3. In a transmitter, comminuted material, a diaphragm having a chamber integral

therewith for said comminuted material, a stationary plunger forming a wall for said chamber, and a plurality of washers between said plunger and said chamber, said washers being loosely disposed so as to form air films between adjacent washers and to form a yieldable closure for holding the comminuted material in said chamber. 30 35

4. In a transmitter comminuted material, a diaphragm comprising a disc having a cup-shaped central depression therein, a second disc of substantially equal diameter having a laterally extending rim cooperating with said depression to form a chamber for said material, a plate disposed between said discs to divide said chamber into compartments and to form a restricted path through the comminuted material, and a plurality of 40 45 loosely disposed washers at the periphery and at one side of each disc for securing said discs and said plate in juxtaposed relation with respect to each other.

In witness whereof, I hereunto subscribe my name this 19th day of January A. D. 1923.

CHARLES R. MOORE.
